UNITED STATES PATENT OFFICE.

HENRY BRAEN, OF PATERSON, NEW JERSEY.

FOLDING CASE.

1,118,326.

Specification of Letters Patent. Patented Nov. 24, 1914.

Application filed May 18, 1914. Serial No. 839,225.

To all whom it may concern:

Be it known that I, HENRY BRAEN, a citizen of the United States, residing at Paterson, in the county of Passaic and State of New Jersey, have invented certain new and useful Improvements in Folding Cases, of which the following is a specification.

This invention relates to extensible and collapsible cases or cabinets, and it consists 10 in certain improvements whereby the several receiving members of such a case or cabinet are capable of moving from the position where they stand superimposed on each other to the position where they stand all 15 with their upper surfaces more or less level, the better or more effectively to display their contents, and whereby on opening or closing the case or cabinet the several receiving members move in synchrony each as 20 a unit of a lever system.

For the purpose of fully explaining the various combinations and arrangements of parts of my invention which are hereinafter embodied in the clauses of the claim I have 25 illustrated the invention in the accompanying drawing in its preferred form, wherein, Figure 1 is a side elevation of the improved case or cabinet, fully open and partly broken away; Fig. 2 is a similar view showing the cabinet, partly open; Fig. 3 is a similar view, showing the cabinet closed; Fig. 4 is a plan view, the cabinet being fully open; and, Fig. 5 is a sectional view illustrating a modification.

35 In said drawings, and referring first to Figs. 1 to 4, *a* is the rectangular body of the cabinet, the same having a bottom wall *b* and four lateral walls *c*, *c'*, of which the wall *c'* is somewhat lower than the other three. The body *a* forms a supporting structure for a system of parts including a plurality of receiving or tray-like members and a cover member and suitable connections between them whereby in the closed 40 condition of the case or cabinet the receiving members will be arranged one above the other and the cover member superimposed upon the body and whereby when the case or cabinet is opened the two receiving members and the cover, which is then inverted and which may form an auxiliary receiving member, stand all substantially at the same level so that their contents are unobstructedly exposed to view. The lower 45 receiving member comprises a pair of end

frames *d* and the tray or receiving member proper *e* resting on said end frames, the whole having a dimension transversely of the case or cabinet somewhat less than the interior transverse dimension of said cabinet, so that said receiving member is capable of some lateral motion in the case or cabinet. To prevent such motion of the receiving member or tray proper *e* with respect to its supporting frames *d*, however, 60 the latter are preferably provided with the upstanding confining lugs *d'*. When the lower receiving member is constructed as described its tray or receiving member proper *e* may be removed from the frames 65 *d* so that access may be had to the contents of the cabinet in the bottom thereof. The upper receiving member or tray consists of the end frames *f* secured permanently to the ends of the tray or receiving 70 member proper *g*. The cover *h* is preferably hollow on its under side so as to form an auxiliary receiving member.

Referring now to the means whereby the two receiving members and the cover are 80 supported on the body *a* and connected with each other, and describing the same as the several parts appear in Fig. 3, *i* designates two pairs of parallel angular levers each fulcrumed in a strip *j*, attached to the inside of an end wall of the case or cabinet, on a horizontal pivot *j'* and having upwardly inclined long arms pivoted to the end frames *f* of the upper receiving member or tray and downwardly extending short 85 arms pivotally connected with the frames *d* of the lower receiving member or tray, the fulcrum of each lever being disaligned with the points of pivotal connection between its arms and said frames *f* and *d*. Thus the 90 levers are adapted to swing up and over to the left for opening the cabinet, from the position in which they appear in Fig. 3 to the position in which they appear in Fig. 1; and in such movement the lower receiving member moves slightly to the right and then to the left, while the upper receiving member moves first up and then down in the arc of a circle, the limit to these several movements being determined by the extremities of the long arms of the right hand levers in Fig. 3 coming to rest upon the fulcrum portions of the left hand levers, whose 95 short arms are slightly offset, as shown, for this purpose. To more equally distribute 100

the strain and insure the upper receiving member *f* remaining rigid and firmly supported when in the open position (Fig. 1) I provide the aforesaid contacting portions 5 of the levers *i* with the interlocking teeth *k*.

The cover *h* is connected at its left lower edge (Fig. 3) with the left upper edge of the upper receiving member by the hinges *l*. When, therefore, it is swung to the open 10 position so that its normal under side is uppermost, it is flush with the upper receiving member and is then supported by contact of what is its left side in Fig. 3 with the left side of the said receiving member.

15 One of the principal objects of this invention is to accomplish a synchronous opening of the case or extension of its several receiving members upon movement of that one thereof which forms its cover. To this 20 end, I extend the extremities of the long arms of the left-hand levers *i* beyond their points of pivotal connection with the upper receiving member and connect such extremities with the cover by the links *m*. It will 25 thus be seen that when the cover is moved on its hinges *l* it obtains a purchase, through the links, on the levers *i* acting to extend or collapse the whole system.

It will be understood that the opening *n* 30 which is afforded above the wall *c'* of the body is mainly provided so that when the several receiving members are extended they may occupy the flatwise position already described and not project materially above the 35 top of the body. For closing this opening when the case or cabinet is closed I provide the wall *o* hinged to an extension *p* of the bottom of the body and connected with the left hand levers *i* by the links *q*. Although 40 the extended system of parts is substantially supported by the contacting levers *i* (especially when interlocked, as herein described) the wall *o* and links *q* will assist in supporting them provided there is means, as 45 *r*, on which wall *o* can rest in the open position.

In the modification shown in Fig. 5 the wall *s* for closing the opening *n* is hinged to the upper edge of the wall *c'*, *t* being links 50 connecting the left hand levers *i* with the wall *s* and corresponding to the levers *q*. In this case, in the open position of the wall *s* the same rests flat against the wall *c'*.

55 My improved cabinet or case has been devised especially as a tool kit to be placed upon the running board of an automobile; but it will be understood that it has many other uses.

60 It will be apparent, in view of the foregoing description, that the opening or closing movement of the cover *h* involves extending or collapsing the entire system of parts of which the cover forms a part, and that the character of the connections is such 65 that throughout the movement all the parts

move together, always under the control of the master member constituted by the cover. The slight movement which the lower receiving member has to the right and left is sufficient so that its upper left corner clears 70 the lower right corner of the upper receiving member as they pass each other, and in the extending movement results in very little space being left between said members. as shown in Fig. 1.

Having thus fully described my invention, what I claim as new and desire to secure by Letters Patent is:—

1. In combination, with a supporting structure, an extensible and collapsible system of parts including a pair of receiving members arranged one above the other, and substantially parallel levers connecting and supporting said members and each fulcrumed between its points of pivotal connection with said members on a horizontal axis in said structure disaligned with said points. 80

2. In combination, with a supporting structure, an extensible and collapsible system of parts including a pair of receiving members arranged one above the other, and substantially parallel levers connecting and supporting said members and each fulcrumed between its points of pivotal connection with said members on a horizontal axis in said structure, one lever being adapted to abut against the other and limit the extending movement of said system of parts. 90

3. In combination, with a supporting structure, an extensible and collapsible system of parts including a pair of receiving members arranged one above the other, and substantially parallel levers connecting and supporting said members and each fulcrumed between its points of pivotal connection with said members on a horizontal axis in said structure, said levers having means to interlock them in the extended position of said system of parts. 100

4. In combination, with a supporting structure, an extensible and collapsible system of parts including a pair of receiving members arranged one above the other, and substantially parallel levers connecting and supporting said members and each fulcrumed between its points of pivotal connection with said members on a horizontal axis in said structure, said levers having toothed means to interlock them in the extended position of said system of parts. 110

5. In combination, with a supporting structure, an extensible and collapsible system of parts including a pair of receiving members arranged one above the other, and substantially parallel levers fulcrumed on horizontal axes in said structure between their ends and having two corresponding short arms and two corresponding long arms, the short arms being disposed angularly relatively to the long arms, and one 120

member being pivoted to the long arms, and the other pivoted to the short arms, of said levers.

6. In combination, with a supporting structure, an extensible and collapsible system of parts including a receiving member, substantially parallel levers each fulcrumed on a horizontal axis in said structure and pivotally connected with said member, a cover member pivoted at one side thereof to one side of the first-named member, and connecting means between the cover member and one of said levers.

7. In combination, with a supporting structure, an extensible and collapsible sys-

tem of parts including a receiving member, substantially parallel levers each fulcrumed on a horizontal axis in said structure and pivotally connected with said member, a cover member pivoted at one side thereof to 20 one side of the first-named member, and a link-connecting the cover member and one of said levers.

In testimony whereof I affix my signature in presence of two witnesses.

HENRY BRAEN.
